[57] **CLAIM**

The ornamental design for a trailer hitch cover, as shown and described.

DESCRIPTION

FIG. 1 is a front elevation view of the trailer hitch cover;

FIG. 2 is a rear elevation view of the trailer hitch cover;

FIG. 3 is a side elevation view of the trailer hitch cover;

FIG. 4 is a top plan view of the trailer hitch cover;

FIG. 5 is a bottom plan view of the trailer hitch cover;

and,

FIG. 6 is a sectional view of the trailer hitch cover shown as it covers a ball hitch, as seen along lines 6—6 in FIG. 3.

The broken lines are for illustrative purposes only and form no part of the claimed design.
